Primary Examiner — Robert M Spear*Assistant Examiner* — Eliza Bennett-Hattan**CLAIM**

We claim the ornamental design for a display terminal, as shown and described.

DESCRIPTION

FIG. 1 is a front perspective view of a display terminal; FIG. 1A is an enlarged view thereof taken along lines 1A-1A of FIG. 1;

FIG. 2 is a rear perspective view thereof;

FIG. 3 is a front view thereof;

FIG. 4 is a rear view thereof;

FIG. 5 is a top view thereof;

FIG. 6 is a left side view thereof;

FIG. 6A is an enlarged view thereof taken along lines 6A-6A of FIG. 6; and,

FIG. 7 is a right side view thereof.

The dash-dash broken lines in the drawings are environmental lines which do not form part of the claimed design. The short dash-long dash lines are boundary lines which do not form part of the claimed design.

The display terminal is shown with a symbolic break in its length. The appearance of any portion of the article between the break lines forms no part of the claimed design.
